UNITED STATES PATENT OFFICE.

JOHN ISBELL, OF WASHINGTON, MISSOURI.

RAIL-JOINT.

1,088,581.

Specification of Letters Patent. Patented Feb. 24, 1914.

Application filed February 18, 1913. Serial No. 749,205.

To all whom it may concern:

Be it known that I, JOHN ISBELL, a citizen of the United States, residing at Washington, in the county of Franklin and State of Missouri, have invented a new and useful Rail-Joint, of which the following is a specification.

The invention relates to improvements in rail joints.

The object of the present invention is to improve the construction of rail joints, and to provide a simple, inexpensive and efficient rail joint of great strength and durability, designed for use as a permanent rail joint for connecting the ends of the rails in the construction or laying of tracks, and capable also of being advantageously employed as an emergency joint for quickly and safely repairing broken rails, and adapted to enable an injured or defective track to be put in proper condition for use in a minimum amount of time and with the least delay of traffic.

With these and other objects in view, the invention consists in the construction and novel combination of parts hereinafter fully described, illustrated in the accompanying drawing, and pointed out in the claim hereto appended; it being understood that various changes in the form, proportion, size and minor details of construction, within the scope of the claim, may be resorted to without departing from the spirit or sacrificing any of the advantages of the invention.

In the drawing:—Figure 1 is a side elevation of a rail joint, constructed in accordance with this invention. Fig. 2 is a reverse plan view of the same. Fig. 3 is a horizontal sectional view of the rail joint. Fig. 4 is a transverse sectional view on the line 4—4 of Fig. 3. Fig. 5 is a perspective view of one of the sections or members of the rail joint.

Like numerals of reference designate corresponding parts in all the figures of the drawing.

In the accompanying drawing in which is illustrated the preferred embodiment of the invention, the rail joint comprises in its construction inner and outer sections or members 1 and 2, each consisting of an angle plate provided at one end with an integral chair 3, and having at the other end a tapered or wedge-shaped portion 4, which operates with the chair of the other section or member of the rail joint. The angle

plates of the sections or members of the rail joint fit upon the bottom flanges of the rails 5 and engage under the heads thereof, as clearly illustrated in Fig. 4 of the drawing. 60 The angle plate of the inner section or member of the rail joint terminates or has its upper edge located at the lower face of the head of the rail, and the angle plate of the outer section or member is extended to approximately the plane of the treads of the rails, the top extension or portion 6 being tapered and presenting oppositely inclined upper faces 7 and adapted to bridge the joint or meeting ends of the rails to carry 70 the wheels across the same and to eliminate jar and vibration and prevent the wheels from breaking down the rail ends. The angle plates also fit against the webs of the rails, and they are secured to the latter by 75 transverse bolts 8 piercing the angle plates and the webs of the rails, which are preferably provided with slightly elongated bolt openings 9, adapted to permit the expansion and contraction of the rails incident to 80 changes in temperature.

Each chair, which extends inwardly with respect to the rails, consists of a horizontal bottom plate receiving and supporting the adjacent rail and provided with a tapered 85 or wedge-shaped flange or engaging portion 10, arranged in spaced relation with the angle plate of its section or member and presenting an inner angularly disposed face 11 for engagement with the wedge-shaped portion 4 of the other section or member of the rail joint. The wedge-shaped portion 4 is tapered outwardly and presents an angularly related side face 12 to coact with the inner face 11 of the wedge-shaped portion 95 10, and when the two sections of the rail joint are assembled, the wedge-shaped portion fits between the flange 11 of the other section or member of the rail joint and the adjacent rail, which is wedged tightly between the coacting sections or members of the rail joint.

The wedge-shaped portion 4 is provided at its outer side face 12 with a plurality of vertical grooves or recesses 13, approximately 105 semi-circular in cross section and adapted to register with a similar groove or recess 14 in the inner angularly disposed face 11 of the wedge-shaped portion 10 to form an opening 110 for the reception of a bolt or pin 15 to prevent the angle plates from receding or moving longitudinally of each other. The bolt

or pin 15, which has a head at its upper end, extends through an opening 16 in the bottom of the chair and projects below the same. The head of the bolt or pin 15 overlaps the 5 wedge-shaped portions of the coacting members or sections, and the lower end of the bolt or pin is provided with a perforation 17, adapted to receive a key 18 for retaining the bolt or pin in place. Any other suitable 10 means, however, may be employed for this purpose.

The chair 3 and the wedge-shaped portion 4 are arranged in spaced relation with each other and with the end faces of the rails, and 15 the sections or members of the rail joint are provided at the center with opposite integral supporting lugs 19, extending inwardly from the lower edges of the angle plates and arranged beneath and presenting flat upper 20 faces to the end portions of the rails and overlapping and supporting the same. The supporting lugs are approximately rectangular and have straight side and end edges, and are arranged in spaced relation with each 25 other and with the chairs and the said lugs terminate in substantially the vertical planes of the inner faces of the angle plates. The chairs are adapted to rest upon two cross ties and the lugs 19 support the ends of the rails 30 between the cross ties and prevent the ends of the rails from sagging. The chairs are provided at opposite sides with integral outwardly projecting approximately horizontal ears 20, preferably located at the end edges 35 of the chairs and provided with spike receiving recesses 21. The ears, which preferably taper outwardly in thickness, have their lower faces arranged in the plane of the lower faces of the chairs, and the latter are 40 provided adjacent to the inner ends of the ears with recesses 22, adapted to afford ample space at the heads of the spikes for enabling the same to be easily driven into the cross ties in fastening the rail joint to the 45 same. While I have illustrated a spike receiving ear at each side of each chair, any number of such spike receiving ears may, of course, be employed.

In assembling the parts, each section or 50 member is placed on one of the rails with the bottom flanges thereof fitting the chair and the angle plate fitted against the side of the rail. The sections are then brought together by moving them longitudinally of the 55 rails in overlapping relation, the wedge-shaped portion 4 of each section or member fitting in the chair of the other section or member. The sections or members are driven together by a small spike hammer, or 60 other suitable tool, and are secured in their adjustment by the bolts or pins 15.

The rail joint besides being adapted for use as a permanent rail joint may be employed as an emergency joint for connecting the two ends of a broken rail, and it will 65 enable a track to be repaired and placed in proper condition in the shortest possible time and with the least delay of traffic. The chair and the coacting wedge-shaped portion are wedged together with sufficient binding 70 force in themselves to make a secure joint without the aid of the transverse bolts. The bolts are an additional factor of security, and any other equivalent fastening means may be employed for this purpose. For instance, lugs may be substituted for the bolts, the lugs projecting from the inner side of the 75 outer angle plate and piercing the webs of the rails, the openings for the lugs being of sufficient size to permit the expansion and 80 contraction of the rails incident to changes in temperature.

What is claimed is:—

A rail joint including inner and outer sections comprising angle plates provided with 85 outwardly extending bottom flanges, the angle plate of the outer section extending to approximately the plane of the treads of the rails and tapered to present oppositely inclined upper faces, said sections being also 90 provided at their opposite ends with inwardly extending relatively heavy rail supporting chairs adapted to be seated upon two adjacent cross ties and each consisting of an integral transversely disposed thick bottom 95 plate provided at the outer end with a flange, and each angle plate being provided at the outwardly extending bottom flange with an enlarged laterally projecting wedge-shaped portion engaging with the flange of the chair 100 of the other section, whereby the rails are clamped at the ends of the joint, the intermediate portions of the bottom flanges of the angle plates being relatively narrow and provided at the central portion of the rail 105 joint with integral inwardly projecting relatively small horizontal lugs of a thickness considerably less than that of the bottom plates of the chairs and arranged to extend beneath the rails and spaced from the said 110 chairs and terminating short of each other in substantially the vertical plane of the inner faces of the angle plates and supporting the terminals of the rails between the cross ties. . . .

In testimony, that I claim the foregoing as my own, I have hereto affixed my signature in the presence of two witnesses.

JOHN ISBELL.
